UNITED STATES PATENT OFFICE

95,402

DESIGN FOR A THERMOMETER BULB PROTECTING CAP

John L. Chaney, Springfield, Ohio

Application February 11, 1935, Serial No. 55,332

Term of patent 14 years

To all whom it may concern:

Be it known that I, John L. Chaney, a citizen of the United States, residing at Springfield, in the county of Clark and State of Ohio, have invented a new, original, and ornamental Design for a Thermometer Bulb Protecting Cap, of which the following is a specification, reference being had to the accompanying drawing, forming part thereof.

Fig. 1 is a front elevation, and Fig. 2 is a top plan view, of a thermometer bulb protecting cap, showing my new design.

I claim:

The ornamental design for a thermometer bulb protecting cap, as shown.

JOHN L. CHANEY.
